ANTENNA FAIR-LEAD

Albert A. Green, Bridgeport, Conn., assignor to
United Aircraft Corporation, East Hartford,
Conn., a corporation of Delaware

Application April 7, 1937, Serial No. 135,470

8 Claims. (Cl. 244—1)

This invention relates to improvements in antenna fairleads and has for an object the provision of an improved means for guiding a radio antenna into and out of the fuselage or hull of an airplane.

A further object resides in the provision in an improved antenna fairlead of the character specified including means extendible beyond the surface of the hull or fuselage to prevent the 10 antenna from contacting the surface of the hull or fuselage while the antenna is being reeled into or out of the body of the airplane.

A still further object resides in the provision in a flying boat of an improved guide means for 15 a radio antenna, said guide means having a water tight connection with the skin or cover portion of the boat hull and extending above the water line when the boat is at rest on the water.

An additional object resides in the provision 20 of an improved antenna fairlead which will effectively insulate the antenna from the portion of the boat through which the antenna passes when it is extended to operative position.

Other objects and advantages will be more 25 particularly pointed out hereinafter or will become apparent as the description proceeds.

In the accompanying drawing in which like 30 reference numerals are used to designate similar parts throughout, there is illustrated a suitable 35 mechanical embodiment of what is now considered to be the preferred form of the idea of the invention. The drawing, however, is for the purpose of illustration only and is not to be taken as limiting the invention, the scope of which is to be measured entirely by the scope of the appended claims.

In the accompanying drawing,

Fig. 1 is a transverse sectional view of a fragmentary portion of an airplane fuselage or hull 40 showing an improved antenna fairlead constructed according to the idea of this invention applied thereto, such portion of the fairlead being broken away to better illustrate the construction thereof.

Fig. 2 is a side elevational view of one form 45 of airplane to which the antenna fairlead may be applied and illustrates one practical position of the antenna with relation to the body of the airplane.

Referring to the drawing in detail, the numeral 10 generally indicates an airplane hull or fuselage. In the illustrative construction shown, the numeral 10 indicates the hull of a passenger-carrying flying boat. The type of flying boat illustrated is provided with a passenger

compartment and with a separate control compartment providing space for the pilots, navigator, mechanic and radio operator. As a matter of convenience, the radio antenna is located near the radio operator and projects through 5 the bottom of the hull of the flying boat at a location at the rear of the control compartment, as is clearly illustrated in Fig. 2. It is to be understood, however, that this location is by way of exemplification only and that the antenna 10 may lead through any portion of the boat in which its location would be desirable or convenient.

In the form of the invention illustrated, the hull is provided at the rear of the control compartment with a transverse bulkhead 12 secured to a bottom frame 14 to which is secured the 15 hull skin or cover 16.

An antenna reel generally indicated at 18 is 20 mounted upon the bulkhead 12 within convenient reach of the radio operator and from this reel the antenna 20 extends through an aperture 22 provided in the bottom portion of the hull.

Between the aperture 22 and the reel 18, there 25 is provided an antenna fairlead or antenna guide generally indicated at 24.

The antenna fairlead 24 comprises an outer tubular member 26 secured at its lower end to the upper end of a flared or frusto-conical member 28 by suitable means such as the screw-threaded union 30. The lower end of the flared member 28 is disposed at an angle to the longitudinal axis of the member and is provided with an annular flange 32 which overlies a portion of the cover or skin 16 surrounding the aperture 22. Preferably a gasket is disposed between the adjacent surfaces of the flange and the cover member and the flange is securely attached to the cover member by suitable means such as the screws 34 to provide a water-tight 30 connection between the lower end of the member 28 and the skin of the hull of the flying boat. The union 30 provides a water-tight connection between the lower end of the tubular member 26 and the upper end of the member 28 35 and the upper end of the tubular member 26 extends above the water line when the boat is at rest in the water. The guide member additionally comprises an inner tubular member 36 40 slidably mounted in the outer tubular member 26 and insulated therefrom by the annular insulating members 38 and 40 disposed within the opposite end of the tubular member 26, and a locking member 42 for restraining the inner 45 50 55

tubular member against movement with respect to the outer tubular member.

The lower end of the inner tubular member 36 is provided with an annular flare 44 within which is seated a gasket 46 for receiving the pointed upper end of the antenna weights 48. The inner tube 36 is resiliently urged downwardly with respect to the outer tube 26 by means of a coiled compression spring 50 surrounding a portion of the inner tube and acting between the upper insulating member 40 secured to the upper end of the outer tube and a collar 52 secured upon the inner tube 36 within the tube 26.

The lock member 42 is a partly cylindrical member rigidly secured at its lower end to the insulating member 40 and insulated from the outer tube member 26. This member extends upwardly above the upper end of the outer tube 26 and is provided at its upper end with a locking slot 54 adapted to receive a handle 56 secured to the upper end of the inner tube 36 so that by rotating the inner tube 36 the handle 56 may be brought within the slot 54 and retain the inner member in its uppermost position against the action of the spring 50. If desired, the ends of the spring 50 may be attached to the tubes 36 and 26 in such a manner that torsional action of the spring will automatically insert the handle 56 into the slot 54 when the antenna is fully retracted.

The antenna reel 18 is shown as provided with a winding knob 58 although it may be motor driven, if desired, and is also provided with a locking lever 60 so that it may be locked to retain the antenna in its fully retracted position as illustrated in full lines in Fig. 1 or at any desired amount of extension from the hull or fuselage of the airplane.

When it is desired to extend the antenna from its fully retracted position, the reel lock is disengaged by the member 60, the handle 56 is disengaged from the slot 54 and rotated out of the slot 54 and the antenna reeled out of the airplane. As the antenna moves out of the airplane, the inner tube 36 follows the weight 48 downwardly until the lower end of the tube projects below the bottom surface of the hull, as is particularly illustrated in broken lines on Fig. 1. In its extended position, the inner tube 36 prevents the antenna weight 48 from slapping against the sides or bottom of the hull under the action of the air stream flowing past the hull and insures that the antenna will fall freely from the airplane without interfering with the hull or becoming entangled.

When the antenna is reeled in, the upper end of the weight 48 contacts the lower end of the extended inner tube member 36 and the force of the spring 50 causes the tube member to support the weight 48 against movement under the influence of the air stream as it is drawn into the interior of the weight receiving member 28. After the antenna has been drawn completely within the airplane and the reel 18 locked to retain it in such retracted position, the handle 56 may be moved into the slot 54 to remove the force of the spring 50 from the antenna and the reel. A certain amount of tension, however, is maintained upon the antenna so that the upper end of the weight 48 is retained in contact with the gasket 46 to provide a water-tight joint between the weight and the lower end of the inner tube member 36. From an inspection of Fig. 1, it will be observed that when the antenna is fully retracted, no portion of the antenna or the

antenna guide projects materially beyond the flush surface of the hull cover 16 and that when the antenna is extended the weighted end thereof is guided firmly and smoothly through the aperture 22 to the exterior of the hull and to such a distance below the hull surface that the weight 48 is entirely free of the hull and will not slap against the surface of the hull as the antenna is released. It will also be observed that the antenna is completely insulated from all portions of the hull.

While there has been illustrated and described a particular constructional form of the idea of the invention, it is to be understood that the invention is not limited to the construction so illustrated and described, but that such changes in the size, shape, material and arrangement of parts may be resorted to as come within the scope of the appended claims.

Having now described the invention so that others skilled in the art may clearly understand the same what it is desired to secure by Letters Patent is as follows.

What is claimed is:

1. In combination with an airplane and a radio antenna extendible through a portion of the surface of said airplane, and provided with a weight at the end thereof, guide means for said antenna providing a water-tight connection between said guide means and the surface of said airplane, and means providing a water-tight connection between said guide means and said weight.

2. In combination with an airplane and a radio antenna extendible through a portion of the surface of said airplane, means for guiding the end of said antenna through said surface to a position in which said end is clear of said surface during the extension of said antenna, a spring for urging said guide means to extended position and means for removing the force of said spring from the tension on said antenna when said antenna is fully retracted.

3. In combination with an airplane and a radio antenna extendible through a portion of the surface of said airplane, means for guiding said antenna through the surface of said airplane comprising an outer tubular member sealed at its lower end to the cover of said airplane, an inner tubular member, within said outer tubular member and a spring for projecting said inner member to position its outer end beyond the surface of said airplane when said antenna is extended.

4. In combination with an airplane and a radio antenna extendible through a portion of the surface of said airplane, means for guiding said antenna comprising an outer tubular member sealed at one end to the cover of said airplane, and an inner tubular member within said outer tubular member and insulated therefrom, resilient means for urging said inner tubular member to a position in which its outer end is projected beyond the surface of said airplane, and means for locking said inner tubular member in its restricted position against the force of said resilient means.

5. In combination with an airplane and a radio antenna extendible through a portion of the surface of said airplane, means for guiding said antenna comprising an outer tubular member sealed at one end to the cover of said airplane, an inner tubular member within said outer tubular member and insulated therefrom, and a spring for projecting said inner tubular member to a position in which its outer end projects beyond

the surface of said airplane, said inner tubular member being provided with a flare at its outer end, and a gasket in said flare for receiving said antenna weight.

5. 6. In combination with an airplane and a radio antenna extendible through a portion of the surface of said airplane and a weight for the end of said antenna, guide means for said antenna comprising a tapered member sealed to the cover 10 of said airplane and providing a receptacle for said weight, an outer tubular member secured to the outer end of said tapered member, an inner tubular member within said outer tubular member and insulated therefrom and a spring for 15 projecting said inner tubular member to a position extending through said tapered member to the exterior of said airplane.
7. In combination with an airplane, a radio antenna extendible through a portion of the surface 20 of said airplane, and an end weight for said antenna, a receptacle within said airplane for

said end weight, an insulated antenna guide having an operative position with its outer end at the inner end of said receptacle, and means operative upon unreeling of said antenna to project the outer end of said guide means outwardly to carry said weight clear of the surface of said airplane and hold said antenna out of contact with said surface. 5

8. In combination with a vehicle hull, and a weighted line extendible through an aperture in the lower portion of said hull, a tubular receptacle secured to said hull surrounding said aperture and projecting upwardly in the interior of said hull to a position above the water line, a movable guide tube in said receptacle surrounding said line, means resiliently urging said guide tube to a position in which it projects beyond the outer surface of said hull to maintain said line clear of said hull surface, and means electrically insulating said guide tube from said receptacle. 10 15 20
